UNITED STATES PATENT OFFICE.

LYNDON O. RAMSDELL, OF DANVERS, MASSACHUSETTS, ASSIGNOR TO THE TURNER TANNING MACHINERY COMPANY, OF PEABODY, MASSACHUSETTS, A CORPORATION OF MAINE.

LEATHER-WORKING MACHINE.

1,377,434.

Specification of Letters Patent. Patented May 10, 1921.

Application filed July 22, 1920. Serial No. 398,162.

To all whom it may concern:

Be it known that I, LYNDON O. RAMSDELL, a citizen of the United States, residing in Danvers, in the county of Essex and State 5 of Massachusetts, have invented an Improvement in Leather-Working Machines, of which the following description, in connection with the accompanying drawings, is a specification, like characters on the

10 drawings representing like parts.

This invention relates to machines of that class in which a rotatable disk or cam provided with an inclined face co-operates with a lever to effect movement of the latter in one direction. Machines of this character are commonly employed for working hides, skins and leather, in which an operating tool is caused to be reciprocated while it is being rotated, the movement of the tool in 15 one direction being effected by the face cam acting on said lever.

In leather working machines of this character as heretofore constructed and known to me, the lever carried a ball which contacted with the face cam. This arrangement created an excessive friction and in time wore a groove in the face of the cam, which produced an uneven and jumpy stroke of the operating tool in its reciprocating 20 motion, with the result that the efficiency of the machine was greatly impaired and the cost of operating the same increased.

The present invention has for its object to increase the efficiency and prolong the life 25 of machines of the character described, and also to enable them to be operated with a minimum of power, and obtain a superior product from the machine.

To this end, the face cam has co-operating 30 with it an antifriction device, which is mounted to rotate in one direction and to oscillate in a direction substantially at right angles to the first-mentioned direction, and said antifriction device is preferably made 35 as a disk or wheel provided with a beveled circumference which is of the same inclination as the beveled or inclined face of the cam.

The beveled wheel or disk is mounted on a 40 substantially vertical pivot, which is preferably mounted in a carrier or frame horizontally pivoted in the lever which actuates the operating tool, the pivot for said carrier or frame being located at one side of

the vertical pivot for the beveled disk or 55 wheel and between the said vertical pivot and said cam.

These and other features of this invention will be pointed out in the claims at the end 60 of this specification.

Figure 1 is an elevation of a sufficient portion of a machine embodying this invention to enable it to be understood.

Fig. 2, a side elevation of the machine shown in Fig. 1 looking toward the left.

Fig. 3, a detail to be referred to.

Fig. 4, an enlarged detail of the cam and the lever operated by it, and

Fig. 5, a front elevation of Fig. 4, looking 70 toward the left.

Referring to the drawing, *a* represents an operating tool, which is mounted on a shaft *b* to rotate therewith and to be reciprocated thereon. The shaft *b* is mounted in a suitable frame *c* and may be provided with pulleys *d* for rotating it.

The operating tool *a* is shown as a cylinder and may be such as commonly used in whitening and buffing machines, being usually provided with a surface layer of emery 80 paper, sand paper or the like, which is not herein shown as it is not necessary to a full understanding of the present invention and does not form part thereof.

The tool *a* is reciprocated on its shaft *b* by a lever 10, which moves it in one direction, and by a spring 12 which moves it in the opposite direction.

The lever 10 is pivoted at 13 to a suitable support 14, represented in Fig. 2 by dotted 90 lines as a bracket which is attached to the frame of the machine, and said lever is turned on its pivot in one direction by a cam disk 15 provided with an inclined or beveled face 16, and mounted on a countershaft 17 95 provided with a pulley 18 for rotating it.

The machine as thus far described is not herein claimed, as it is old in the art of hide and leather working machinery, but in such old machines, the lever 10 usually carried a 100 ball which engaged the inclined face 16 of the cam disk 15, with the attending disadvantages above noted.

In accordance with the present invention, the beveled face 16 of the cam 15 has co-operating with it an antifriction device which is capable of movement in two directions at an angle to each other.

The antifriction device is preferably made as herein shown and consists of a disk 20 provided with a beveled or inclined circumference 21, which is of the same inclination as the beveled face 16 of the cam which it bears against. The disk 20 is mounted to turn freely on a vertical pivot 22 supported by a frame or carrier 23, which in turn is pivotally mounted in a yoke 24 attached to the lever 10 by bolt 25 or otherwise. The yoke 24 is offset so that the pivot 26 for the frame or carrier 23 is eccentrically located with respect to the pivot 22 for the bevel disk 20, and is located between the pivot 22 and the cam disk 15, as clearly shown in Fig. 4.

By reference to Fig. 4, it will be seen that as the cam disk 15 is revolved, the inclined or beveled face 16 thereof is relieved from 20 being cut or grooved by the bevel circumference 21 of the disk, inasmuch as the disk is free to tilt or turn on the pivot 26 of the carrier or frame 23, to follow the bevel face 16 of the cam and thereby keep the bevel circumference 21 of the disk in the same relation to the inclined face 16 of the cam during each rotation of the latter, while at the same time said disk is free to turn or rotate on its pivot 22 in a direction substantially at right angles to that in which it is tilted by the cam disk. As a result of this construction, the friction between the cam disk 15 and the disk 20 is reduced to a minimum and the life of the machine is 35 materially prolonged. Also less power is required to run the machine, a lighter spring 12 can be used to keep the disk 21 in contact with the cam 15, and a superior grade of work is produced on the machine because 40 of the absence of jerky or jumpy movements of the operating tool, especially when rotated at a relatively high speed, as for instance at 150 revolutions per minute, said tool in the present instance having a perfectly even and smooth reciprocating movement.

The invention is herein shown as embodied in a machine in which the reciprocating operating tool is a plain cylinder, but 50 it is not desired to limit the invention to

the particular form of machine herein shown.

Claims—

1. In a machine of the character described, in combination, a reciprocating tool, a lever for moving it in one direction, a spring to move it in the opposite direction, a rotatable cam coöperating with said lever and having an inclined face, a rotatable disk provided with a beveled circumference coöperating with the inclined face of said cam, a carrier in which said disk is mounted to rotate in one direction, and a yoke attached to said lever and in which said carrier is mounted to turn in another direction at an angle to the first-mentioned direction.

2. In a machine of the character described, in combination, a reciprocating tool, a lever for moving it in one direction, a spring to move it in the opposite direction, a rotatable cam coöperating with said lever and having an inclined face, a rotatable disk provided with a beveled circumference coöperating with the inclined face of said cam, and a carrier for said disk pivotally connected with said lever to permit said disk to be tilted by said cam in a direction at an angle to that in which it turns on said carrier.

3. In a machine of the character described, in combination, a reciprocating tool, means for moving it in one direction, a lever for moving it in the opposite direction, a rotatable disk having an inclined face, an anti-friction device coöperating with the inclined face of said disk and mounted on said lever to rotate in one direction and to be tilted or turned in a direction at an angle to that in which it is rotated.

4. In a machine of the character described, in combination, a rotatable disk provided with an inclined face, an anti-friction device coöperating with the inclined face of said disk, and a device in which said anti-friction device is mounted to rotate in one direction and to be turned in a direction at an angle to that in which it is rotated.

In testimony whereof I have signed my name to this specification.

LYNDON O. RAMSDELL.
